CLAIM

The ornamental design for a candle holder as shown and described.

DESCRIPTION

FIG. 1 is a front elevation view of a candle holder showing my new design, the rear, left and right elevation view being a mirror image thereof;

FIG. 2 is a top plan view thereof;

FIG. 3 is a bottom plan view thereof;

FIG. 4 is a front bottom perspective view thereof;

FIG. 5 is a front top perspective view thereof; and,

FIG. 6 is a front elevation cross-sectional view thereof, taken along line 6-6 of FIG. 1.

1 Claim, 5 Drawing Sheets
